UNITED STATES PATENT OFFICE.

CHARLES KLEIN, OF SYRACUSE, NEW YORK.

BRUSH-CLEANING ATTACHMENT FOR BOTTLES.

SPECIFICATION forming part of Letters Patent No. 498,475, dated May 30, 1893.

Application filed November 28, 1892. Serial No. 453,357. (No model.)

To all whom it may concern.

Be it known that I, CHARLES KLEIN, of Syracuse, in the county of Onondaga in the State of New York, have invented new and useful Improvements in Brush-Cleaning Attachments for Bottles, &c., of which the following, taken in connection with the accompanying drawings, is a full, clear, and exact description.

10 This invention relates to improved devices applied to receptacles of mucilage or other liquid substances and designed to express the excessive substance from the brush in its withdrawal from the receptacle. And the invention consists in the novel construction and combination of parts hereinafter described and set forth in the claim.

15 In the annexed drawings Figure 1 is a vertical transverse section of a mucilage bottle 20 provided with my improved brush wiping devices. Fig. 2 is an inverted plan view of the cover of said bottle, and Fig. 3 is a top plan view of the bottle minus its cover.

Similar letters of reference indicate corresponding parts.

R— represents the bottle or analogous receptacle for the mucilage or other liquid substance.

25 C— denotes the cover which is detachably secured to the aforesaid receptacle in any suitable manner. This cover is provided with the large opening —a— for the introduction of the brush, and from said opening extends a slot —a'— for the purpose hereinafter explained.

30 b— denotes a spring-bow formed of suitable band of spring metal and extending around the opening —a— and secured edge-wise to the under side of the cover at one side 40 of said opening, and having its free ends extending along the corresponding sides of the slots —a'— where they are bent transversely at right angles downward to form the jaws —c—c. Said spring bow is attached to the

45 cover —C— at one side of the opening a— preferably by means of a lip —l— extending from the edge of the spring-bow and passing through a slot —l'— in the cover as shown

in Fig. 2 of the drawings, the protruding end of the said lip being pressed down 50 tightly onto the cover to obtain a firm hold thereon. The jaws —c—c— are yieldingly sustained in their position by the spring-bow —b— and thus adapted to press simultaneously on both sides of brushes of different 55 thicknesses and in order to render the jaws adjustable to greater or less resistance I attach to the cover —C—, a screw-threaded thimble —e— and insert therein a set screw —d—, the inner end of which is swiveled in 60 a longitudinal slot in the free portion of the spring-bow. By turning said screw the spring-bow is contracted or expanded and thereby the jaws —c—c— are set closer or farther apart as may be desired. 65

In using the described devices the brush is introduced into the receptacle —R— through the opening —a— of the cover, and in withdrawing the brush from the receptacle the brush is first pushed laterally into the slot 70 —a'— and thus brought between the jaws —c—c— and then in drawing the brush upward the surplus mucilage or liquid substance is either wiped or squeezed from the brush and retained in the receptacle. 75

Having described my invention, what I claim as new, and desire to secure by Letters Patent, is—

In combination with the receptacle —R—, the cover —C— provided with the large opening —a— and slot —a'— extending from said opening, and the spring bow —b— formed separate from the cover and secured to the under side of the cover at one side of the aforesaid opening and terminating with jaws 80 —c—c— along opposite sides of the slot —a'— and sustained yieldingly laterally by the spring-bow, substantially as described and shown. 85

In testimony whereof I have hereunto 90 signed my name this 26th day of November, 1892.

CHARLES KLEIN. [L.S.]
